UNITED STATES PATENT OFFICE.

LEON E. LA BOMBARD, OF CHELSEA, MASSACHUSETTS, ASSIGNOR TO SPECIALTY AUTOMATIC MACHINE COMPANY, OF CHELSEA, MASSACHUSETTS, A CORPORATION OF MASSACHUSETTS.

MACHINE FOR MAKING BOXES.

1,346,899.

Specification of Letters Patent. Patented July 20, 1920.

Application filed February 20, 1918. Serial No. 218,319.

To all whom it may concern:

Be it known that I, LEON E. LA BOMBARD, a citizen of the United States, and resident of Chelsea, in the county of Suffolk and 5 State of Massachusetts, have invented certain new and useful Improvements in Machines for Making Boxes, of which the following is a specification.

This invention relates to the manufacture 10 of paper boxes of the type known as flat folded boxes or cartons, and the invention refers particularly to machines for rapidly converting cut and creased blanks into tubes which issue from the machine in flat form, 15 ready for shipment, to be afterward opened or expanded to receptacle form.

The principal object of the invention is to provide a machine of this character which is capable of operating on very small blanks 20 to produce boxes of the smallest size used for commercial purposes.

A further object is to provide improvements which will prevent any lateral shifting of the blanks while being carried through 25 the machine, no matter what may be the sizes of the blanks.

A further object is to provide a machine 30 which continuously advances the blanks but shifts the control thereof from one side portion of the blank to another side portion thereof in order to keep accurate control of blanks of very narrow width.

Another object is to provide a machine of 35 this character with an improved stacking mechanism which keeps control of the very narrow flat blanks as they issue from the folding mechanism in flattened tubular form.

With these and other objects in view, my 40 invention consists in the improvements which I shall now proceed to describe and claim.

Of the accompanying drawings:

Figures 1, 2, 3 and 4, together, represent 45 a longitudinal sectional view of the complete machine, Fig. 1 showing the end of the machine where the blanks are supplied by any suitable feeder, and Fig. 4 which slightly overlaps Fig. 3, showing the end where the flat folded boxes leave the machine.

50 Figs. 5, 6, 7, and 8 are plan views of those portions of the machine shown respectively in Figs. 1, 2, 3 and 4.

Fig. 9 represents a section on line 9—9 of Figs. 1 and 5.

Fig. 10 represents a detail elevation of a 55 portion of the machine shown in Fig. 6 and duplicated and similarly illustrated also in Figs. 5 and 7.

Fig. 11 is a detail elevation of parts shown near the middle of Fig. 6. 60

Fig. 12 is a detail elevation of parts shown near the middle of Fig. 7.

Fig. 13 represents a section on line 13—13 of Fig. 7 on a larger scale.

Fig. 14 is a sectional elevation of gearing 65 hereinafter described.

Fig. 15 is a sectional detail of means for frictionally transmitting rotation to several of the shafts hereinafter described.

Fig. 16 is a plan view of one form of 70 blank adapted to be folded to flat tubular or carton form by this machine.

Figs. 17, 18, 19 and 20 are views to illustrate successive operations upon the blank shown in Fig. 16. 75

Figs. 21, 22 and 23 are detail views, hereinafter referred to, of mechanism for counting the folded boxes.

Similar reference characters designate 80 similar parts in all of the views.

The frame of the machine may be of any suitable form or design. For present purposes it is sufficient to illustrate the side bars thereof at 20.

The main carrier belt 21, which is quite 85 thick as best shown in Fig. 13 and made of leather or other suitable material is a long one, mounted at one end (Fig. 1) on a pulley 22 carried by shaft 23, and at the other end (Figs. 3 and 4) on a pulley 24 carried 90 by shaft 25. A shorter upper belt 26 is mounted on pulleys 27, 28 (Figs. 1 and 5) carried by shafts 29, 30, respectively. The belt 26 is much narrower than belt 21 as shown in Figs. 5 and 9. Blanks such as 95 shown in Fig. 16 are fed, one at a time, between the belts 26, 21, where they meet between the pulleys 27, 22, by any suitable mechanism not necessary to illustrate.

The shafts 29, 23, are provided with intermeshing gears, one of which is shown at 31 in Fig. 5. The other end of shaft 23 is provided with a bevel gear 32 driven by a bevel gear 33 carried by a shaft 34 mounted in

brackets 35 supported by one of the side bars 20. Said shaft extends practically the entire length of the machine as shown in Figs. 5, 6, 7 and 8.

5 Each of the shafts 29, 30, is mounted in bearings carried by arms 36 secured by set screws 37 to transverse rods 38, 39 which are supported by frame brackets 40 (Figs. 1 and 5). Mounted in each pair of arms 36 is a 10 shaft 41 having its mid-length portion screw threaded. The two shafts 41 carry sprockets 42 for a connecting chain 43. Slidably mounted on each screw shaft 41 is a hub 44 having a pin (not necessary to illustrate) 15 engaging the screw thread so that when the two shafts are rotated in one direction or the other by grasping the upper stretch of chain 43 and pulling it toward either sprocket, the hubs 44 will be adjusted to 20 ward one side or the other of the machine, for a purpose hereinafter explained. Depending from the hubs 44 are feet or brackets 45 which support a cage of rolls comprising a bar 46, side plates 47 and rolls 48, 25 the latter bearing upon the upper surface of the lower or operative stretch of belt 26. The rolls 48 are preferably arranged in pairs as shown in Fig. 1, and in practice are yieldingly mounted as shown in Fig. 7 of my 30 application Serial No. 137535, filed December 18, 1916.

The upper stretch of the lower belt, throughout its length as shown in Figs. 1, 2 and 3, runs on rolls 49 mounted on pintles 35 supported by side plates 50 rising from a bar 51, the latter being supported by cross or tie rods 52 of the machine frame. The side plates 50, as shown in Figs. 9 and 13, extend far enough above the plane of the tops of 40 the belt-supporting rolls 49 to act as guides which prevent any lateral shifting of the belt out of an exact pre-determined path. Said plates 50 however can not, for a reason presently explained, prevent lateral shifting 45 of the belt unless the latter is of the extra thickness such as shown in Fig. 13. The belt 21 has a series of longitudinal grooves 53 (Figs. 5 and 9) with which certain pickers or flap lifters coöperate as hereinafter described. For such coöperation it is important that the belt can not shift laterally. The side plates, acting as belt-guides as explained insure correctness in the path of movement of the belt.

55 Machines of this general type, to be commercially successful, must be capable of running at high speed. At such speed a carrier belt for the blanks, if made of leather of the single thickness ordinarily obtainable, 60 has a tendency to shift sidewise or "wabble" and is also "jumpy" in its action. The result is that it sometimes works onto the flanges of the supporting rolls when flanged rolls are employed. These tendencies of 65 ordinary belts are enhanced by the fact that

as leather belts of any material length are always made of lapjointed pieces, and as the pieces vary in quality, the belt as a whole is quite irregular and some sections tend to shift to one side more than other sections. 70 Then when a section pushes against whatever is employed to guide the belt, the reaction or resistance of that guide tends to cause the belt to rise or bend laterally, causing it to bulge or buckle. These difficulties I 75 have overcome by making the belt 21 so thick in proportion to its width (properly termed double-thick) that it can not buckle laterally as the result of any amount of back pushing of either of the guides 50. It is important that the belt as a whole shall not 80 shift laterally because if it did it would cause lateral shifting of the blanks carried thereby and interfere with the proper folding of the blanks on their crease lines. 85 Therefore the belt is made of uniform width as indicated in the plan view figures, and said width is such as to just fill the space between the guides 50. The result is that no portion of the belt can shift laterally or be 90 crowded so as to bulge or buckle.

The lower belt 21 is wide and needs no lateral adjustment. The upper or first control belt 26 is laterally adjustable, as by mechanism presently described, to insure 95 correct folding of small blanks. Other upper belts (79, 133) farther along in the machine and yet to be described, are laterally adjustable similarly, but independently of belt 26. In other words, each upper belt 100 (and its cage of pressing rolls) is adjusted independently. When the chain 43 is operated to rotate the two screw shafts 41, arms 54 of hubs 44 which engage annular grooves 55 in the hubs of pulleys 27, 28 (Fig. 105 5) shift said pulleys along their shafts. The pulley 27 has a splined connection (Fig. 1) with its shaft 29 because this pulley drives the belt 26.

When lateral adjustment of the upper belt 110 is to be effected, it is desirable to first temporarily lift the belt, its pulleys, shafts 29, 30 and 41, and the cage of rolls 48, so that friction on belt 21, due to the weight of those parts, shall not interfere with accurate 115 adjustment. To this end I provide means for slightly rocking the rods 38, 39, manually to swing their arms 36 up far enough to lift all the parts which are connected to said arms to separate belt 26 from belt 21. 120 As the same means are duplicated for the several upper belt structures, I employ the same reference characters in Figs. 6 and 7 as are used in Figs. 1 and 10 to designate the manual lifting mechanism. Referring 125 particularly to Figs. 5 and 10, arms 56, 57 are clamped respectively to rods 38, 39, and overlap each other. A pin 58 projects from one arm into a slot 59 in the other arm so that actuation of one arm will actuate the 130

other. A screw 60 passes through a hole 61 in arm 56 and engages a threaded hole in arm 57, said hole 61 being considerably larger than said screw, but less in size than the head of the screw or a washer under said head. The arm 56 has a handle 62. The screw 60 is employed simply to tightly secure the overlapped arms so they can not swing. When said screw is loosened, pressure exerted on the arms, by bearing down on handle 62, rocks the rods 38, 39, to swing the arms 36 up, thus temporarily lifting the necessary parts while chain 43 is being actuated to effect lateral adjustment of pulleys 27, 28, belt 26, and the cage of rolls 48.

Blanks of the kind illustrated in Fig. 16 are creased or scored on lines *a*, *b*, *c*, *d*, which may be relatively spaced as shown in said figure or differently spaced relatively if the final box is not to be square in cross section when opened and filled. In order that the blanks may be properly folded, and the completed boxes can then be conveniently opened for insertions of their contents, it is often desirable that all four creased lines shall be "broken," that is, so bent on their creased lines that the folding and opening above mentioned can be properly and conveniently performed. Therefore, by mechanism shown in Figs. 1 and 5, the blanks between belts 21, 26 are "broken" on two creased lines although those two lines are not the ones on which the blank is folded by mechanism shown in the other figures and yet to be described. To effect this preliminary breaking when the user of the machine desires it, I provide two inclined lifter fingers 63, 64, (Figs. 5 and 9) which coact with two disks 65, 66 free to rotate on a rod 67 and adjustable thereon for different styles of blanks, as by suitable collars. The lifter finger 63 is adjustably supported in a bracket 67 which, in turn, is adjustably supported on a pin 68 projecting from one of the plates 50, and the lifter finger 64 is adjustably supported by a bracket 69 which, in turn, is adjustably supported on a pin 70 projecting from the other plate 50.

As it is not essential that the lower belt shall be as wide as the blanks, I find it desirable to provide a roll 71 under the disk 66 (Fig. 9), said roll being mounted idly on a pin projecting from one of the plates 50, so that when the blanks being operated on are of a type such as indicated at *x*, and the machine parts are adjusted to run the blanks through with said portions of the blanks projecting as shown in Fig. 9, said side portions will be nipped firmly between disk 66 and roll 71 while the finger 64 is turning up the edge portion of the blank and breaking the crease *a* (Fig. 17).

The machine is illustrated as adjusted for operation on very small blanks having narrow edge flaps as indicated at *e* in Fig. 16,

Each blank passing through so much of the machine as so far described, is converted from the flat form shown in Fig. 16 to the form shown in Figs. 9 and 17. As the next step is to apply glue (a generic term employed herein for any suitable adhesive) to the under surface of flap *e*, I provide means for positively turning the flap *e* down after it has been bent up or broken as described. The opposite marginal portion of the blank is of such area that it automatically returns to a substantially horizontal plane after passing disk 65 and finger 63. The blanks are fed to the machine in such lateral positions that the belts 21, 26, grip portions *f* or *g* thereof preferably the latter. To turn down the flap *e*, I employ a blade 72 having a beveled front end 73, said blade projecting rigidly as shown in Figs. 1 and 5 from a pin 74, supported by a bracket 75 mounted on the top of a suitable glue box 76. A glue wheel 77 carried by a shaft 78 applies a film of glue, to the flap *e* of the blank, which flap is turned down by the portion 73 of the blade and then guided along by the lower straight edge of the blade to contact with the glue wheel.

At this time the blanks have been broken on the lines *a*, *c*, (Figs. 9 and 17) and have been returned to substantially flat form as shown in Fig. 18, and have had glue applied to their flaps *e*. As they are then to be folded on other lines, the lines *b*, *d*, by mechanism to be described hereinafter, and as the blanks are so small that no wide upper belt can be used, I shift the carrying control of the blanks to portions other than those which were under the control of belt 26. For this I employ a belt 79 which constitutes the second control belt, Figs. 5 and 6 showing how it occupies a different lateral position relatively to the first control belt 26. And, as presently explained, the belt 79 can be laterally adjusted relatively to and independently of the belt 26 so as to meet the requirements of differently cut and creased blanks.

At one end, the belt 79 is supported by a pulley 80 (Fig. 5) mounted on shaft 30 at one side of pulley 28, and at the other end by a pulley 81, carried by a shaft 82 (Figs. 2 and 6) having a gear 83 meshing with a similar gear 84 under it and carried by a shaft 129 hereinafter referred to. A tightener roll 85 for the belt 79 is carried by a suitably supported arm 86.

At one side of and parallel with belt 79, and as shown in Figs. 5 and 6 as in alignment with the belt 26, is a comparatively short belt 87 supported at one end by a pulley 88 splined on a shaft 89 (Figs. 1 and 5) and at the other end, (Fig. 2) by a pulley 90. Said pulley is mounted on a pin 91 supported by side plates extending from a block 92 attached to one end of a bar 93

having side plates 94 which support rolls 95 bearing on the upper surface of the lower or operative stretch of the belt 87. 96 (Fig. 2) designates a cage of rolls for 5 the operative stretch of belt 79, said cage being similar to the one described for belt 26. Said cage is longer than the one for belt 87 and extends from close to pulley 81 on shaft 82 (Figs. 2 and 6) to close to pulley 80 on shaft 30 (Figs. 1 and 5). Said cage is supported at one end by a bracket 97 (Fig. 2) having a smooth-bore aperture through which a screw-threaded shaft 105 hereinafter described passes, and near the 10 other end has a bracket (behind bracket 106 in Fig. 1) hung on shaft 101. The shaft 89 (Figs. 1 and 5) is mounted in arms 98 of a rod 99 mounted to be rocked slightly in bearings in frame brackets 100, 20 (Figs. 2 and 6) and said arms provide bearings for the screw shaft 101. The shaft 82 is mounted in arms 102 of a rod 103 mounted to be rocked slightly in bearings in frame brackets 104, and said arms provide 25 bearings for the screw shaft 105. The bar 93 has a bracket 106 hung on shaft 101 (Figs. 2 and 1). By rocking the two rods 99, 103 in the same manner as described in connection with the rods 38, 39, the bar 93, 30 the roll cage 96, and all parts carried thereby, will be raised slightly to lift belts 79, 87, away from belt 21. As the devices for effecting such rocking are the same as already described in connection with Figs. 5 and 10, 35 the same reference numerals are employed as in Fig. 6.

The screw shafts 101, 105, have sprockets connected by a chain 107 so that, by grasping said chain and pulling it one way or the 40 other, both of said shafts will be simultaneously rotated. On the threaded portion of shaft 101 is a hub 108, Fig. 5, having an arm 109 engaging an annular groove in the hub of pulley 88. Said hub 108 has an arm 110 provided with a roll 111 for keeping belt 87 taut.

When a blank reaches the position where glue is applied to the under surface of its flap *e* by glue wheel 77, it is flat as in Fig. 50 18, and has been taken control of by belt 79 which bears on section *h* or *i*, preferably the latter. The section *g* however is under belt 87 for a time, and therefore the blank is held from twisting as it is carried along 55 between belt 21 and belts 79, 87, while the blank is being bent or broken on line *b*, and the folding operation commences. This bending up of the blank on line *b* is effected by a folder arm 112 (Fig. 6) having a shank 113 adjustably connected with a bracket 114, which, in turn, is adjustably supported on a pin 115 projecting from one of the side plates 50. Said folder arm 112 turns or folds the blank to carry its portions *f*, *e*, to position to pass under the belt

117 presently described. The portions *g*, *h* *i* of the blank continue to be carried along on belt 21 under the coöperating pressure of upper belt 79, the up-turned portion of the blank being guided over on top of a tapering shoe 116 (Figs. 2 and 6) the thin tip end of which extends far enough to guide the folded line of the blank until the latter is well under belt 117. 70

The belt 117 (Figs. 2, 6 and 11) is 75 mounted on pulleys 118, 119, carried by a bar 120 which is rigidly connected to the inner end of a sleeve 121 adjustably supported by a bracket 122 rising from one of the side bars 50. A tightener for the belt is 80 indicated at 123. The pulley 119 is carried by a shaft 124 extending through sleeve 121 and having a pulley 125 at its outer end. The pulley 118 is mounted on a stud shaft 126 carried by bar 120. By adjusting the 85 sleeve 121 which rigidly carries bar 120, the inclination of the belt relatively to the belt 21 can be varied so that the lower stretch of belt 117 will properly and gradually fold down the in-turned portions *f*, *e*, of the 90 blank to the position shown in Fig. 19.

The pulley 125 is driven by a belt 127 (Fig. 6), said belt being driven by a comparatively large pulley 128 carried by shaft 129 (Fig. 2) having bevel gear connection 95 130 with shaft 34. The pulleys 125, 128 are of such relative sizes that belt 117 travels considerably faster than the blank is being carried along by belts 21, 79, so as to secure a forwardly wiping action on the portion *f* 100 to counteract the preceding tendency of folder arm 112 and shoe 116 to hold this portion back and cause a slightly askew folding on line *b*. In other words, if the nature of the blank material is such that the 105 first step of folding on line *b*, by the arm 112 and shoe 116, tends to be laterally inclined, or askew, the faster traveling belt 117 which completes the folding on line *b*, counteracts that tendency by drawing the 110 folded over portion forwardly to position determined by the crease of line *b*.

To hold the in-turned portion of the blank down and guide it under the third upper belt 133 presently described, I provide 115 a small shoe or guide 131 adjustably connected by a link 132 to the bar 120.

The third upper belt 133 is mounted at one end on a pulley 134 carried by shaft 82 (Figs. 2 and 6) and at the other end on a 120 pulley 135 carried by a shaft 136 (Figs. 3 and 7) having a gear meshing with other gearing hereinafter described. Control of the blank is taken by this third belt after the blank has been folded as shown in Fig. 125 19, so that there will be nothing in the way to interfere with the next operation of folding the portion *i* over as shown in Fig. 20. The mechanism for doing this final folding will be described hereinafter. 130

- The shaft 136 is mounted in bearings provided in arms 137 secured to a rod 138 supported by frame brackets 139. Mounted in said arms is a screw threaded shaft 140.
- 5 Another screw threaded shaft 141 is carried by arms 142 secured to a rod 143 supported by frame brackets 144. The two rods 138, 143 have means for slightly rocking them, for the same purpose as already described in connection with the rods 38, 39 in Fig. 5, and therefore said means bear the same reference numerals in Fig. 7 as in Figs. 5 and 10.
- The two screw shafts 140, 141 have sprockets connected by a chain 145 whereby the two shafts may be simultaneously rotated manually. A nut hub 146 on shaft 140 has an arm 147 engaging an annular groove in the hub of pulley 135, and a nut hub 148 on 10 shaft 141 has an arm 149 engaging an annular groove in the hub of pulley 134, whereby manual actuation of chain 145 will effect lateral adjustment of the belt 133. At the same time, the roll cage for said belt is 20 shifted, said cage comprising a bar 150 (Fig. 3) having side plates supporting the pintles of rolls 151, said bar being hung on the shafts 140, 141 by brackets 152, 153, said brackets being so connected to the hubs 25 146, 148, as to be shifted laterally with said hubs.
- When the blank leaves the control of the second or intermediate upper belt 79 and the control shifts laterally to the third upper belt 133, said blank is in the condition 30 or form shown in Fig. 19, and the completion of the folding to the Fig. 20 form is performed by the mechanism or devices which I shall now describe.
- 35 A bracket 154 (Fig. 7) supported by one of the lower side plates 50, is formed or provided with a tongue 155 which as shown in Figs. 7 and 12 and as indicated by dotted lines in Fig. 3, extends down into one of 40 the grooves 53 in lower belt 21 so that the portion *i* of the blank will ride up onto said tongue. It then rides up the incline 156 supported by bracket 154. Another bracket 157 is supported by side plate 50 and carries a vertical plate 158 (Figs. 7 and 13) by means of the shank 159 of the latter. Said plate has a thin shoe 160 projecting from it. A folder arm 161 has a shank 162 adjustably supported by bracket 45 55 157. As the blank portion *i* passes up the incline 156, its portion *h* passes under the inclined lower edge of plate 158 (Fig. 12) and then under shoe 160 (Figs. 12 and 13). The portion *i* then passes onto or against 60 65 arm 161 and is folded over thereby in the direction of the arrow (Fig. 13), said portion, after passing plate 158, being turned in by said arm 161 until the free end of the latter delivers it to be acted upon by belt 163. The preliminary folding of the blank
- on line *d* is effected by the members 156, 158, 161, to and beyond the position indicated in Fig. 13, and the completion of said fold to the position indicated in Fig. 20 is effected by the belt 163. One end of the 70 belt 163 is mounted on a pulley 164, idly mounted on a pintle carried by a bar 165 (Figs. 7 and 12), and the other end of the belt runs on a driven elongated pulley 166 hereinafter referred to. The bar 165 has a lateral arm or shank 167 which is adjustably secured to a bracket 168 rising from one of the side plates 50. The other end of the bar 165 carries a pulley 169 bearing on the lower stretch of belt 163. A suitably mounted roll 170 keeps belt 163 taut. By adjusting the bar 165, the pulley 164 can be set at any such height as may be desired to cause the portion of the belt from pulley 164 to pulley 169 to run in such an 85 inclined direction as required to take the portion *i* of the blank under it and complete the folding thereof, while the portion of the belt from pulley 169 to pulley 166 will act to press the marginal portion of the 90 section *i* of the blank down on the section or portion *e* which has the glue on its upper surface.
- In a machine of this type, it is essential 95 that the upper belts 26, 79, 87 and 133 shall be quite narrow, to enable small blanks as described to be folded, the control passing from one to another of the belts. Such narrow belts wear much more rapidly than the wide lower belt 21. Therefore their 100 surface speed would be gradually reduced if their driving pulleys and shafts were to be positively driven at a uniform speed, and it would then be impossible to carry the blanks through straight if the surface speed 105 of said upper belts were to differ from that of the main lower belt 21. To overcome this I provide means which tend to frictionally drive the driving shaft of each upper belt at a speed slightly exceeding that 110 of belt 21, the friction between the upper belts and the lower belt then holding the speed of the upper belts down to that of the lower belt. As said means are the same for each of the four upper belts, a description 115 of one will suffice for all. The one chosen is belt 26. As shown in Fig. 1, the pulley 27 is slightly larger than pulley 22. Shaft 23 carrying pulley 22 is positively driven at a uniform speed by the long shaft 120 34 (Fig. 5) through bevel gearing 32, 33. Shafts 23, 29 have intermeshing gears, the upper one, carried by shaft 29, being shown at 31 in Figs. 5 and 15. Gear 31 is not keyed to its shaft, but is held against an 125 annular shoulder 171 of the shaft by a friction disk 172 splined on the reduced portion 173 of the shaft, the latter being threaded for a nut 174 having a set screw 175 for holding it when adjusted. A spring 130

176 confined between the nut and disk holds the gear 31 with sufficient force to tend to rotate the gear and its shaft 29 at the same speed. But as the belts 21, 26, are in sufficient contact so that the former holds the latter down to its speed, the gear 31 slips relatively to disk 172 and the two belts travel at the same surface speed. Of course as the narrow upper belt wears, the amount of such slip decreases until possibly there will be no slip at all when the upper belt has been worn down to its last practical thickness.

The drive of shaft 82 for belt 79 has been described.

The shaft 89 having pulley 88 for belt 87 is provided with a gear 177 (Fig. 5) meshing with another gear under it (not shown) carried by shaft 78 (Fig. 1). Said shaft is driven by the long shaft 34 through the medium of bevel gearing 178.

The shaft 136 having pulley 135 for belt 133 is provided with a gear 179 (Figs. 4, 7 and 8) meshing with a gear 180 carried by shaft 25, the latter having bevel gearing connection 181 with the long shaft 34.

Each of the gears 177, 83 and 179, is mounted on its shaft in the same manner as just described in connection with gear 31, and therefore the same reference numerals are employed for the nuts and springs, to indicate that each driving shaft for each of the four upper belts is frictionally driven by mechanism such as shown in Fig. 15.

The three chains 43, 107, and 145 can be independently operated manually to laterally adjust the upper belts 26, 79 and 133 respectively to locate said belts in their exact relative lateral positions to suit the width of the blanks to be run through, and the relative spacing of the crease lines of such blanks. How operation of chain 43 effects lateral adjustment of belt 26 has been described. In the same manner, belt 79 is adjusted by chain 107 because the latter rotates screw shafts 101, 105. On shaft 105 is a nut hub 182 (Fig. 6) connected to cage bracket 97 (Fig. 2), and having an arm 183 extending into an annular groove in the hub 184 of pulley 81. Near the other end of the roll cage 96 for belt 79 is a bracket similar to and behind the bracket 106 in Fig. 1. The nut hub of such bracket of the roll cage 96 is shown at 185 in Fig. 5. At the end of the roll cage 96 shown in Fig. 1 is a bracket 186 as indicated by dotted lines in said figure. In Fig. 5 a portion of the belt 79, and the tightener roll thereof, are broken away to show the bracket 186. Said bracket

supports the arm 86 of the tightener, and also carries an arm 187 entering an annular groove in the hub 188 of pulley 80. By these devices and connections the belt 79, and its roll cage, are laterally adjusted by operating chain 107.

By similar devices and connections previously described, the belt 133 and its roll cage 150, 151 (Figs. 3 and 7) are laterally adjusted.

The belt 87 and its roll cage are short and may be laterally adjusted by hand.

As shown in Figs. 3, 4 and 7, I provide a plate 190 suitably supported adjustably by a pin 191 and having teeth or fingers extending into the grooves of belt 21 as indicated in Fig. 4 so as to lift the folded blanks from said belt and guide them between two rolls 192. These rolls are so mounted that their nip is far enough above the plane of travel of the folded blanks issuing from between belts 21, 163, to bend or curve said blanks up as they pass from said belts to the rolls. I have found in practice that this insures straight travel of the blanks so passing. Since the narrow upper belt 163 usually bears upon the overlapped portions of the blank, where it is thickest, the blanks tend to turn laterally or travel askew as they leave the belts if free to continue in the same plane of travel. This tendency is overcome by bending or curving them as described.

The rolls 192 deliver the folded blanks between belts 193, 194 (Figs. 4 and 8) which, in turn, deliver them onto a belt 195 which travels so slowly that they are overlapped thereon and are carried in this overlapped condition under a pressing belt 196. The belts 195, 196, are of any desired length, and the upper one may be driven positively or merely by the friction of the moving articles beneath it. The lower belt 195 is mounted at one end on a roll 197 carried by a shaft 198 having a worm wheel 199 meshing with a worm 200 carried by a shaft 201 which extends under a portion of shaft 34 (Figs. 7 and 8) and is driven by the latter by means of a belt and cone drive mechanism, one of the cone pulleys being shown at 202 in Fig. 7, carried by shaft 34. The outer portion of belt 195 runs on pulleys or rolls 203 supported by extension frame bars 204. The belt 196 is mounted on rolls 205, carried by a relatively light frame consisting of bars 206 and a cross rod 207 connected to bars 204 by links 208.

A bracket or casting (Figs. 4, 8, 21 and 22) suitably supported by the frame of the machine, comprises a vertical plate 209 and a shelf-like portion 210, the latter providing bearings for the stud shaft of the belt pulley 166, and the upper one of the two rolls 192, and the shaft 211, of the pulley 212 which drives belt 193. The other end of the belt 193 runs on an idle pulley 213, with intermediate guiding and tightener pulleys 214, 215, 216. The pulleys 213, 214 are mounted on stud shafts supported by a bar 217 having a slot 218, said bar being carried by an arm 219 mounted to oscillate

on shaft 211. A stud at the lower end of arm 219 passes through the slot 218 and is fitted with a nut 220 (Fig. 8) whereby the bar can be secured to the arm in adjusted position with the pulley 213 more or less close to the pressing belt 196. When an adjustment is made, the slack of the belt is taken up by the pulley 215 which is carried by an arm 221 adjustably connected with arm 219.

The short belt 194 below belt 193 is mounted at one end on a pulley 222 at the lower end of arm 219 and at the other end on a pulley 223 mounted on a stud under the bracket shelf 210.

A plate 224 adjustably mounted on a pin 225 serves to guide the blanks carried by the coacting stretches of belts 193, 194. If desired, a second similar guide plate may be positioned opposite the other side edges of the belts.

To yieldingly and adjustably counterbalance the arm 219 and the bar 217 and parts carried thereby, I provide said arm 219 with a downwardly projecting fixed lug or bar 226 (Fig. 4) having a tension spring 227 connected to its lower end the other end of the spring being adjustably connected, by a threaded rod 228 and nut 229 with a suitably supported fixed bracket or rod 230 (Fig. 8).

To guide the folded blanks and insure proper stacking under the pressing belt 196, I provide a pair of yielding shoes, each comprising a spring blade 231 attached to the under surface of a block or hub 232 secured by a set screw 233 to a pin 234 projecting from the end of bar 217. Said shoes bear on the thinner portions of the folded blanks each side of the overlapped and consequently thicker portions thereof, and prevent their turning askew. I sometimes find that one of the shoes may be omitted with good results and do not limit myself to the use of two. When two are employed they extend in opposite directions as shown in Fig. 8.

In operation, the stacker mechanism above described, and illustrated in Figs. 4 and 8, keeps the folded blanks or flat boxes folded and closed until they have passed to the belt 196 which holds them so until their glue lines become set. Said stacker mechanism permits rapid folding because it accumulates the boxes rapidly as they are formed from flat blanks, and reduces their speed of travel in overlapped condition. This is due to the slow speed of travel of receiving belt 195 (as by means of the worm gearing described) compared with the speed of travel of the belts which carry the blanks while being folded, resulting in the folded blanks being deposited on the belt 195 in the form of a row of overlapping articles.

In practice, the swinging frame which

carries the belt 193 will be somewhat lower than shown in Fig. 4. Then, as the overlapped blanks reach belt 196, the latter and its carrying frame will be lifted up, while at the same time free to gravitate with more or less pressure on the row. If desired, the height of the belt 196 and its carrying frame may be regulated by any suitable adjusting mechanism, and the belt 196 might also be positively driven.

The driving mechanism of the machine as a whole, and of the stacker mechanism, is shown in Figs. 4, 8 and 14. A shaft 235 having a pulley 236 at one end for a driving belt and a hand wheel 237 at the other end, has a pinion 238 (Figs. 4 and 14) meshing with the gear 180 of shaft 25. Secured to shaft 25 near gear 180 is a gear 239 meshing with a small gear 240 carried by the shaft 241 of the elongated pulley 166, whereby said pulley and the short belt 163 are driven. The gear 240 meshes with and drives a gear 242 the stud shaft 243 of which is supported by the bracket portion 210. The gear 242 meshes with a pinion 244 of shaft 211 which carries the elongated pulley 212 for driving the belt 193. Said gear 242 also meshes with a pinion 245 (Fig. 21) at the end of the shaft of the upper roll 192, and said shaft has a toothed portion or pinion 246 meshing with a similar pinion 247 of the lower roll 192, whereby said rolls are driven. The intermeshing teeth of pinions 246, 247, are long enough to prevent disengagement when the lower roll 192 is shifted away from the upper roll by a folded box passing between them. The lower roll is carried by a pair of levers 250 one of which is shown in Fig. 22, pivoted at 251 and acted upon by a suitable spring 252 so that the lower roll will be normally held yieldingly up against the upper roll but capable of being depressed slightly by a passing box.

The rear end of the lever 250 shown in Fig. 22 is operatively connected to the lower end of a slide 253 mounted in a fixed guideway 254 and carrying a pawl 255 held by a spring 256 in engagement with a toothed disk 257 rotatively mounted between two ears 258 of the guideway 254. The disk has an insulated pin 259 extending through it to coact as presently described with the inner ends of two contact plugs 260 carried by the ears 258. A suitable detent pawl for the disk is indicated at 261.

Wires 262 connect the contact plugs (Figs. 21 and 22) with a magnet 263 (Fig. 23) supported by a bracket 264 rising from the block 232 of shoe 231. The mechanism shown in Figs. 21, 22 and 23 is omitted from Figs. 4 and 8 to avoid confusion thereof.

The armature 265 of the magnet is pivoted at 266 and has a stop pin 267 capable of being projected far enough across the

path of boxes passing under shoe 231 to arrest one or more boxes.

The operation of this counting mechanism is as follows:

5. Supposing the disk 257 has 25 teeth, and that it is actuated the distance of one tooth each time a blank passes between the rolls 192 on their way to the slowly traveling belt 195 (Fig. 4) where the blanks accumulate overlapped in a row as hereinafter described. So long as the circuit completing pin 259 is away from between contacts 260 the arrester pin 267 will remain raised and will stop no boxes on the belt 195. But 15 when the pin 259 arrives between the two contacts, the circuit through wires 262 and the magnet will be completed and the arrester pin 267 will be shifted down so that the next box, or a small plurality of boxes, 20 will be held back so as to create a little pile of boxes on the belt, but not enough of a pile to interfere with the passage of the same under belt 196 (Fig. 4). As soon as further operation of lever 250 results in 25 rotating the disk to carry the pin 259 beyond the contacts 258, the arrester pin 267 will rise and permit the passage of the boxes in regular overlapped positions until the pin 259 again reaches the contacts. An 30 operative sitting at the machine beyond the belt 196 is able to gather the boxes up in bunches of twenty-five (when the disk 257 has that number of teeth) and place them in the cartons or packing cases, counting the 35 bunches as she proceeds, because the regularly spaced little piles, due to the arresting action of pin 267, causes spaces that are easily seen.

As the operation of the several parts of 40 the machine has been explained in connection with the description of their structures, a description of the operation of the machine as a whole will be unnecessary.

Having now described my invention, I 45 claim:

1. A box folding machine having, in combination a thick blank-carrying belt, means for supporting the operative stretch of said belt, edge guides for insuring travel of the 50 belt in a straight path, said guides being spaced apart a distance to simultaneously guide both edges of the belt and the belt having a thickness to prevent it from being laterally buckled by edge contact with the guides, and means for folding blanks while they are carried by the belt.

2. A machine of the character described comprising a pair of parallel bars, rolls supported by said bars, a blank-supporting belt 60 mounted on said rolls, the upper edges of the bars extending above the plane of the tops of the rolls to provide edge guides for insuring travel of the belt in a straight path, and means coöperating with said belt for

making boxes, said belt having a thickness 65 to prevent it from being laterally buckled by the guides.

3. A machine of the character described comprising a single wide belt having a longitudinal groove, means for insuring travel of 70 the belt in a straight path, a finger extending into said groove of the belt for lifting a portion of a blank carried by said belt, and means coöperating with said belt for folding boxes.

4. A machine of the character described comprising a single wide belt having longitudinal grooves, edge guides for insuring travel of the belt in a straight path, a finger extending into one of said grooves of the 80 belt for lifting a portion of a blank carried by said belt, and means coöperating with said belt for folding boxes.

5. In a box making machine, a wide lower belt for the blanks, an upper relatively narrow belt, a roll cage for holding the operative stretch of the upper belt toward the lower belt, a pair of screw threaded shafts, nut hubs on said shaft, means for simultaneously rotating both of said shafts, and connections 90 whereby rotation of said shafts will adjust the upper belt and roll cage laterally upon the lower belt.

6. In a box making machine, a wide lower belt for the blanks, an upper relatively narrow belt, a pair of screw threaded shafts, each having a sprocket, nut hubs on said shafts, an endless chain mounted on said sprockets for simultaneously rotating both of said shafts, and connections whereby rotation of said shafts will adjust the upper belt laterally upon the lower belt.

7. In a machine of the character described, means for forwarding blanks singly, means for turning a portion of each blank over 105 upon an underlying portion, a belt for completing the folding of the over turned portions of the blanks, and means for driving said belt at a faster speed than the speed of travel of the blanks.

8. In a machine of the character described, a main lower blank-carrying belt, means for partially folding blanks carried thereon, an upper belt for completing the folding of the blanks, and means for driving said upper 115 belt at a faster speed than the speed of travel of the main lower belt.

9. A box making machine comprising a lower belt, a plurality of upper belts one beyond the other and occupying different lateral positions relatively to the lower belt to shift the control of the blanks from one side to the other, and means for operating on different lateral portions of the blanks successively while the blanks are being carried through the machine by said belts.

10. A box making machine comprising a lower belt, a plurality of upper belts one be-

yond the other and occupying different lateral positions relatively to the lower belt, and means for folding blanks which are caused to travel by said belts, each of said 5 upper belts being independently adjustable laterally.

11. A box making machine having a plurality of groups of blank-forwarding and folding instrumentalities, said groups occupying different lateral positions to shift the control of the folding operation from one side to the other of the blanks, and means for adjusting said groups independently of each other.
- 15 12. In a box making machine, a plurality of groups of mechanism each of which includes means for causing blanks to travel and means for folding the blanks while so traveling, said groups occupying different 20 lateral positions to shift the control of the folding operation from one side to the other of the blanks, and means for laterally adjusting each of said groups independently of the other.

- 25 13. A box making machine comprising a lower belt, a plurality of upper belts one beyond the other and occupying different lateral positions relatively to the lower belt, means for folding blanks which are caused 30 to travel by said belts, each of said upper belts having a roll cage for holding its operative stretch toward the lower belt, means being provided for independently adjusting each upper belt and its roll cage laterally.

- 35 14. A blank folding machine comprising a lower belt, means for causing blanks to travel with said belt with the edges of the blanks projecting beyond said belt, means for breaking the blanks on pre-determined 40 lines, and a roll for supporting the portion of each blank which projects beyond the edge of the belt at the point where breaking occurs.

- 45 15. A blank folding machine comprising a wide lower belt, three upper belts, one beyond the other, to coöperate with the lower belt, and means for operating on different lateral portions of the blanks successively 50 while the blanks are being carried through the machine by said belts.

16. In a blank folding machine, upper and lower coöperating blank-carrying belts, means for frictionally driving the upper belt at a speed exceeding that of the lower belt, and folders for operating on the blanks 55 while they are being carried through the machine by said belts.

17. A box making machine having a carrier belt, means for folding blanks on different 60 lines successively, and means for shifting control of the blanks laterally to permit proper operation of the folding means.

18. A box making machine having a plurality of folding instrumentalities to oper-

ate successively on blanks, means for carrying the blanks singly and continuously past said folding instrumentalities, and means for shifting control from one side to the other of the blanks during their passage.

19. A box making machine having a main lower blank-carrying belt, a plurality of upper belts coöperating with the lower belt to forward the blanks, said upper belts being located in different positions longitudinally 70 of the lower belt and in different lateral positions relatively thereto, and means for folding the blanks on different lines as they are forwarded.

20. A box making machine having a main lower blank-carrying belt, a plurality of upper belts coöperating with the lower belt to forward the blanks, said upper belts being located in different positions longitudinally 75 of the lower belt and in different lateral positions relatively thereto, and means for folding the blanks on different lines as they are forwarded, means being provided for laterally adjusting said upper belts.

21. In a box making machine, upper and lower belts for carrying the blanks, means for adjusting one belt laterally relatively to the other, and means for temporarily relieving pressure between the belts during 90 lateral adjustment.

22. In a box making machine, a wide lower belt for the blanks, an upper relatively narrow belt, means for laterally adjusting the upper belt, and means for temporarily raising the upper belt during lateral adjustment thereof.

23. In a box making machine, a pair of coöperating blank-forwarding belts, means for positively driving one of said belts, and frictional driving mechanism geared to exert a tendency to drive the other belt at a higher speed than the positively driven belt, said frictional driving mechanism being constructed to slip to permit the contact of said belts to hold the actual speed of the 105 frictionally driven belt down to that of the positively driven belt.

24. In a box making machine, a wide lower blank-carrying belt, means for positively driving it, an upper narrow belt coöperating with the lower belt to forward the blanks, and frictional driving mechanism geared to exert a tendency to drive the upper narrow belt at a higher speed than that of the lower wide belt, whereby reduction 115 of thickness of either belt due to wear will be compensated for.

25. A box making machine comprising a belt having a longitudinal groove, means coöperating with said belt for forwarding 125 blanks and folding them, and a guide for directing the folded blanks away from the belt at its delivery portion, said guide hav-

ing a projection entering said groove of the belt.

26. A box making machine comprising a belt having a plurality of longitudinal grooves, means coöperating with said belt for forwarding blanks and folding them, and a plate tangential to the delivery end of the belt, said plate having projections entering the grooves of the belt.

10 27. In a box making machine having upper and lower belts which carry folded blanks as boxes, and a pair of rolls for receiving and delivering the boxes from the belts, said rolls being mounted so that their nip is above the plane of travel of the boxes issuing from said belts, whereby the boxes are curved upwardly as they are delivered.

28. A box making machine comprising continuously movable blank-forwarding 20 belts and folders coöperating therewith to convert blanks singly into folded boxes, a receiving belt for the boxes, means for operating the receiving belt at a relatively slow speed, a presser belt coöperating with the receiving belt, and a yielding frame having a pair of coacting belts to transfer the boxes from the first-mentioned belts to the receiving belt.

29. A box making machine comprising continuously movable blank-forwarding 30 belts and folders coöperating therewith to convert blanks singly into folded boxes, a receiving belt for the boxes, means for operating the receiving belt at a relatively slow speed, a presser belt coöperating with the receiving belt, a yielding frame having a pair of coacting belts to transfer the boxes from the first-mentioned belts to the receiving belt, and means for adjustably counter- 35 balancing said yielding frame.

30. A box making machine comprising continuously movable blank-forwarding 40 belts and folders coöperating therewith to convert blanks singly into folded boxes, a receiving belt for the boxes, means for operating the receiving belt at a relatively slow speed, a presser belt coöperating with the receiving belt, a yielding frame having a pair of coacting belts to transfer the boxes from the

first-mentioned belts to the receiving belt, 50 and a shoe carried by said yielding frame to direct the boxes under the presser belt.

31. A box making machine comprising continuously movable blank-forwarding belts and folders coöperating therewith to convert blanks singly into folded boxes, a receiving belt for the boxes, means for operating the receiving belt at a relatively slow speed, a presser belt coöperating with the receiving belt, a yielding frame having a 55 pair of coacting belts to transfer the boxes from the first-mentioned belts to the receiving belt, and a guide parallel with the edges of said coacting belts.

32. A box making machine comprising continuously movable blank-forwarding 60 belts and folders coöperating therewith to convert blanks singly into folded boxes, a receiving belt for the boxes, means for operating the receiving belt at a relatively slow 65 speed, means for transferring the folded boxes to the receiving belt in overlapping positions, and means for temporarily arresting movement of regularly spaced boxes on the receiving belt to create visible interruptions in the row of overlapping boxes.

33. A box making machine comprising continuously movable blank-forwarding 70 belts and folders coöperating therewith to convert blanks singly into folded boxes, a receiving belt for the boxes, means for operating the receiving belt at a relatively slow speed, means for transferring the folded 75 boxes to the receiving belt in overlapping positions, and means for temporarily arresting movement of regularly spaced boxes on the receiving belt to create visible interruptions in the row of overlapping boxes, said arresting means comprising a stop movable 80 toward and from the receiving belt, an elec- 85 tron magnet for controlling the position of said stop, a counter actuated by the boxes, and electrical connections between said counter and magnet.

In testimony whereof I have affixed my 90 signature.

LEON E. LA BOMBARD.
